UNITED STATES PATENT OFFICE

2,592,367

FUEL INJECTION SYSTEM

George B. Wood, Jr., Springfield, Mass., assignor
to American Bosch Corporation, Springfield,
Mass., a corporation of New York

Application November 13, 1946, Serial No. 709,603

6 Claims. (Cl. 103—41)

1

This invention relates to fuel injection systems and more particularly to such systems wherein a plurality of fuel injection pumps are employed whereby the mechanical load on the engine is balanced.

An object of the invention is to provide a fuel injection system having a master pump and one or more slave pumps wherein the quantity of fuel delivered and the timing of all of the pumps is controlled by the controls for the master pump.

Another object of the invention is to provide a fuel injection system of the type set forth wherein in a plurality of pumps are employed with all of the controls on one of the pumps whereby merely a single adjustment of the controls is necessary for adjusting all of the pumps and yet a double pump construction is provided for balancing the drive forces or mechanical loads on the engine.

Other objects and advantages of the invention will be apparent from the following description taken in connection with the accompanying drawing. It will be understood that many changes may be made in the details of construction and arrangement of parts without departing from the spirit of the invention as expressed in the accompanying claims. I, therefore, do not wish to be limited to the exact details of construction and arrangement of parts shown and described, as the preferred form has been shown by way of illustration only.

Referring to the drawing:

In the drawing there is shown a diagrammatic view, partly in section, showing one form of fuel injection system embodying the invention.

Referring more particularly to the drawing, the fuel injection system shown comprises a master pump 1, a slave pump 2 and a nozzle 3.

The nozzle 3 may be of any suitable conventional nozzle or accumulator nozzle type.

The fuel delivery lines 4, 5 and 6 are provided between the pumps and connecting the pumps to the nozzle 3.

The pumps 1 and 2 are adapted to receive fuel from the usual type fuel supply tank through the fuel line 7 which has branches 8 and 9 connecting said line to the pumps 1 and 2 respectively, and fuel is adapted to pass through said line and branches as shown by the arrows in the drawing.

The slave pump 2 comprises the housing 10 having the annular fuel sump 11 which is connected to the branch 9 of the fuel supply line 7, and the barrel 12 in which is reciprocably mounted the plunger 18a and which barrel is provided

with the ports 13 connecting the fuel sump 11 with the bore 14 of the barrel 12 which forms the pumping chamber of the pump and which is connected with the fuel delivery line 4.

- 5 The master pump 1 comprises the housing 15 having the fuel sump 16 connected to the branch 8 of the fuel supply line 7 and contains the barrel 17 in which is mounted the plunger 18 which plunger is adapted to reciprocate in the bore 19 in the barrel 17. The barrel 17 is provided with the annular spill groove 20 which is connected by the port 21 to the fuel sump 16 and the spill ports 22 which connect the bore 19 with said sump 16.
- 15 The plunger 18 of the master pump 1 is of double helix type, that is, it is provided with helices 22a on its opposite sides, only one of which is shown, and said plunger 18 is also provided with the bore 23 communicating with the bore 20 of the barrel 17 at its upper end and which bore is connected by the bore 24 extending through the reduced portion 25 of the plunger at its lower end below the spill edge 33 of the plunger 18.
- 25 The fuel drain line 26 is provided with the branches 27 and 28 and is adapted to drain off any leakage or excess fuel.
- The barrel 17 is provided with a gear segment in engagement with the control rack 29 whereby
- 30 said barrel may be adjusted by adjustment of said control rack for adjusting the quantity of fuel delivered by both pumps and the gear 30 operates rack teeth on the barrel for adjusting the barrel vertically for timing the delivery of both pumps. From this it will be seen that the quantity of fuel delivered by both pumps is controlled by rotating the barrel of the master pump 1 by means of the control rack 29 which operates a gear segment on the barrel and the reciprocating or vertical adjustment of the barrel by means of the gear 30 operating the rack teeth on the barrel adjusts the delivery timing for both pumps.

40 At the upper end of the pump 1 is provided the delivery valve member 31 which is in the form of an annular flexible spring disc member 45 which is secured to the member 32 which extends into the upper end of the bore 19 and which has an opening therethrough adapted to be aligned with the fuel delivery line branch 5.

50 In the operation of the pumps as the plungers move upward on their pumping stroke, the plunger 18a in the pump 2 closes off the fill port 13 at about the same time the plunger 18 closes off the annular spill groove 20. The plungers continue to move in the bores 14 and 19 respectively

and fuel is pumped through the lines 4 and 5 through the bore or hole 23 and port 24 in plunger 18 and out through the metering spill ports 22 until the helix on the plunger 18 closes off the metering ports 22 and as the plungers continue to move in, fuel is delivered to the nozzle through the fuel delivery lines 4, 5 and 6 until the spill edge 33 of the plunger 18 passes the bottom edge of spill groove 20 which then spills in the usual manner.

It will be noted that the start of pumping and the end of pumping of both pumps are controlled by the metering events of the master pump.

While only a single slave pump has been shown in conjunction with the master pump, it will be obvious that additional slave pumps could be employed if desired.

From the foregoing it will be seen that I have provided simple, efficient and economical means for obtaining all of the objects and advantages of the invention.

Having described my invention, I claim:

1. In a fuel injection system, a pair of fuel injection pumps, one of said pumps being a master pump and the other of said pumps being a slave pump and controlled through control of said master pump, a fuel delivery line common to both of said pumps, said pumps each including a bore and a plunger adapted to be reciprocated in said bore, the plunger of said master pump having a spill port communicating with said common delivery line whereby said spill port will bypass fuel pumped by both pumps.

2. In a fuel injection system, a pair of fuel injection pumps adapted to be mounted to balance the mechanical load on the engine, one of said pumps being a master pump, the other of said pumps being a slave pump and controlled through control of said master pump, a fuel delivery line common to said pumps, a fuel supply line common to said pumps, said pumps each including a bore and a plunger adapted to be reciprocated in said bore, said master pump having a spill port communicating with said common delivery line whereby said spill port will bypass fuel pumped by both pumps.

3. In a fuel injection system, a pair of fuel injection pumps, one of said pumps being a master pump and the other of said pumps being a slave pump and controlled through control of said master pump, a fuel delivery line common to both of said pumps, said pumps each including a bore and a plunger adapted to be reciprocated in said bore, the plunger of said master pump having a spill port therein and extending below the spill edge of said plunger, said port communicating with said common delivery line whereby said spill port will bypass fuel pumped by both pumps.

4. In a fuel injection system, a pair of fuel injection pumps, one of said pumps being a master pump and the other of said pumps being a slave pump and controlled through control of said master pump, a fuel delivery line common to both of said pumps, said pumps each including a bore and a plunger adapted to be reciprocated in said bore, the plunger of said master pump having a spill port communicating with said common delivery line whereby said spill port will bypass fuel pumped by both pumps and means for controlling the quantity of fuel bypassed through said spill port.

5. In a fuel injection system, a pair of fuel injection pumps adapted to be mounted to balance the mechanical load on the engine, one of said pumps being a master pump, the other of said pumps being a slave pump and controlled through control of said master pump, a fuel delivery line common to said pumps, a fuel supply line common to said pumps, said pumps each including a bore and a plunger adapted to be reciprocated in said bore, said master pump having a spill port communicating with said common delivery line whereby said spill port will bypass fuel pumped by both pumps and means for controlling the quantity of fuel bypassed through said spill port.

6. In a fuel injection system, a pair of fuel injection pumps, one of said pumps being a master pump and the other of said pumps being a slave pump and controlled through control of said master pump, a fuel delivery line common to both of said pumps, said pumps each including a bore and a plunger adapted to be reciprocated in said bore, the plunger of said master pump having a spill port therein and extending below the spill edge of said plunger, said port communicating with said common delivery line whereby said spill port will bypass fuel pumped by both pumps and means for controlling the quantity of fuel bypassed through said spill port.
